UNITED STATES PATENT OFFICE.

ROBERT E. MANLEY, OF YORK, PENNSYLVANIA.

ENGINE STAND.

Application filed October 29, 1921. Serial No. 511,349.

This invention relates to engine stands for supporting motors so that the same may be operated upon for repair, overhauling, etc. The object of the present invention is 5 to provide an engine stand which will give maximum convenience in repairing a motor and furnish maximum accessibility.

A further object of the invention lies in the provision of a cross-piece supported 10 from the carriers by distance pieces so that the cross-piece may be adjusted toward and away from the arms of the stand, as well as being capable of being positioned at any angle thereto within the usual limits required.

Further objects of the invention will be apparent from the following description and include the several improvements illustrated and described and covered by the 20 claims.

There are a number of engine stands on the market today, some of them being quite satisfactory with certain types of engines, but which are not adaptable for use with 25 other types. With the present stand any motor of any type from a light two-cylinder buckboard motor to the very heavy automobile truck motors may be accommodated. This great range of service is possible due 30 to the various adjustable features of the present stand, for example, the standards are movable with relation to each other; the heads are adjustable vertically; the arms are pivoted so as to swing through the entire 35 360°; the carriers are slidable throughout the length of the ways or arms; the distance pieces are secured to the carriers and to the cross-piece by pivotal means so as to be secured at any desired angle; and the supporting or spacer members are movable 40 freely in the longitudinal slot of the cross-piece and are adjustable at any distance therefrom.

As shown in the perspective view, the 45 motor is secured to two of the carriers in the same manner as it is secured to the chassis frame, while at the other end the supporting members and the cross-piece hold the front end of the motor in a position of convenient accessibility, the supporting members attaching directly to the inner face of the gear housing, the panel for which is removed before the motor is attached to the frame.

Fig. 1 is a perspective view of my device 55 in its preferred form, and

Fig. 2 is a central vertical section through the cone clamp and head of the standard.

Fig. 3 is a perspective of the device shown with a different motor and with the pivoted 60 arms turned thru approximately 180°.

My device consists of three main parts, namely, the frame A, the standards B, and the truck C. The frame is pivoted to the standards and the latter are mounted in 65 pedestals 10 and 11, respectively, one of which may be permanently secured to the truck, while the other is adjustable thereon to correspond to the different widths of chassis in common use. The truck is prefer- 70 ably furnished with casters or wheels so as to be conveniently moved from place to place.

The truck consists of a pair of wheeled bases 12 and 13 which may be of different 75 lengths as shown, each consisting of a pair of angle irons secured together at either end by their fastening to the caster support 15 and intermediately by the angle clips 16 to which are secured the parallel beams 17 80 forming the longitudinal members of the truck.

Each of the pedestals consists of a single casting providing a wide base 19 grooved to fit the corners of the bars 17 and recessed to 85 form four legs to reduce the friction of the pedestal against the bars when the former is moved. From the base 19 rises a socket 20 centrally strengthened on either side by a triangular stiffening member 21, the socket 90 being split on either side and in proximity to the stiffening member 21 so that one slot will be to the right of one of these stiffening members, while the other will be to the left of the opposite member, in order that 95 each split portion shall consist of a semi-cylinder and an integral stiffening web.

The standard B consists of two telescoping portions 22 and 23, the former being secured in the socket of the pedestal by a bolt 100 24, which not only binds the member 22 to the pedestal, but also draws together the two split portions of the socket. The inner and smaller member 23 of the standard receives at its upper end the head 25 which may be secured to it in any desired manner and at its lower portion is perforated with a number of holes 26 adapted to engage with a 105

pin 27 passing through the upper end of the member 22 so as to hold the head of the telescoped standard at the desired adjusted height.

- 5 The head 25 is provided at one side with a cup member 29 into which is fitted the cone clamp 30 which is provided in its outer flat face with a grooved recess 31 to receive the arms 32 forming the longitudinal members 10 of the frame A. A bolt 33 having a reduced end 34 is mounted centrally of the head and cup member and passes through the cone clamp 30 as well, the shoulder between the larger portion of the bolt and the 15 reduced portion 34 abutting against the outer face of the angle iron arm 32 which is secured against such shoulder by means of the nuts 35 so that the bolt, clamp and angle iron arm move as a unit, and may for all 20 purposes be considered as integral. The end of the bolt 33 that passes through the head is threaded to receive a nut 37 which is loosened by means of a socket wrench, such as 38 to permit the turning of the 25 frame on its pivots and when this nut 37 is tightened, the frame is locked in position by means of the frictional engagement between the cone clamp 30 and the correspondingly shaped recess in the cup 29.
- 30 The supporting arms 32 pivoted as just described are capable of swinging throughout the entire 360° of a circle so that when a motor is mounted upon these arms in the way illustrated, the motor can be swung in 35 to any desired position and the frame may be locked to maintain it at the chosen angle by merely tightening the nuts 37. A pair of carriers 40 are slotted to slide upon the arms 32 and may be secured at any 40 distance from the pivot by tightening the set screw 41. These carriers each has an inwardly extending projection 42 serving as a bracket to support the rear end of the motor and for this purpose the bracket is 45 slotted to receive the standard bolt which secures the usual integral ear of the fly wheel casing to the chassis frame. In some motors the rear end is not supplied with ears overlapping the chassis bars, but is secured 50 to them by means of special fittings. In such cases as this an angle clip is mounted upon the bracket end of the carrier and the rear end of the motor frame is secured to this angle clip in well known manner.
- 55 The front end of the motor is secured to the frame A by means of connections with a cross piece 45 which consists in a pair of parallel bars 46 and 47 secured to and spaced from each other by the bolts 48 and 60 the spacing sleeves 49 mounted thereon, this construction forming a cross piece having a central slot in which the supporting or suspending members 50 are freely slidable longitudinally of the cross piece. Each of these 65 supporting members consists of a threaded

rod having a flattened circular perforated end 51, this rod being threaded throughout its entire length as shown, and being secured in the slot of the cross piece by means of washers 52 and nuts 53.

The cross piece 45 is supported above the carriers 40 by means of distance or spacing pieces 55, each of which has a smooth central portion 56 which may be cylindrical or may be squared for convenience in holding it, 75 while the ends are threaded right and left handed to receive nuts 57 for engagement with the cross piece and similar nuts 58 which secure the distance piece to the bracket end 42 of carriers exactly similar to those 80 previously described, all of these nuts being provided with the usual washers.

While it is not intended that the cross piece should ever be arranged other than parallel to the upper faces of the carriers, 85 it will be noted that the carriers may be arranged at different distances from the pivots of the arms, and since the distance pieces 55 are cylindrical, and therefore have a pivotal engagement with both the cross piece and the carriers, the cross piece may be arranged at any desired angle to the arms. It will usually not be necessary to thus angle the cross piece since in normal 90 operation it will be arranged parallel to the plane of the flange of the gear housing and the supporting members 50 will be adjusted vertically and horizontally so that the perforations in the flattened ends 51 will register with the bolt holes in such flange so that the bolts 60 of the normal equipment 95 of the motor may be used to secure the motor to the supporting members. On the pedestal 11 is mounted a bracket 65 which is secured to the socket 20 by the bolt 24 and is perforated at its lower end to receive the shaft of a bolt 66 having a solid integral head 67. This bolt 66 is threaded through a bridge member 70 clamped to the beams 17 by means of the thumb screws 71 and the bolt or adjusting member 66 is provided with a small handle 72 at its end so that it is not necessary to carefully adjust the distance between the two pedestals, since by 100 securing the bridge 70 and by turning the handle 72, the movable pedestal may readily be brought to the exact location desired.

When the frame A is moved so that the bars 32 are vertical it might appear that a very great stress was thrown upon the four 105 set screws 41. This however, is not the case as, due to the pivotal connection of the distance pieces 55 with both the cross-piece 45 and the carriers 40, the carriers will tilt slightly so as to firmly clamp against the now vertical arms so that the stress upon the set-screws is almost negligible.

What I claim is:

1. In an engine stand, the combination of supporting means, a cross-piece, suspending 110

- means adjustably secured to said cross-piece, and means for adjustably securing said cross-piece spaced from said supporting means.
5. 2. In an engine stand, the combination of supporting means, a cross-piece, means for securing said cross-piece at any one of a plurality of distances from said supporting means, and suspending means secured to said cross-piece and horizontally and vertically adjustable with respect thereto.
3. In an engine stand, the combination of supporting means, a slotted cross-piece, means for securing said cross-piece at any one of a plurality of distances from said supporting means, and suspending means secured to said cross-piece and slidably mounted within said slot and horizontally and vertically adjustable with respect to said cross-piece.
20. 4. In an engine stand, the combination of a pair of spaced arms, carriers slidably mounted on said arms, and work-supporting means secured to each of said carriers at a single point to one side of said arms whereby said carriers are caused to bind against said arms when the work is in place on said supporting means.
5. In an engine stand, the combination of a pair of spaced arms, a carrier slidably mounted on each of said arms, a bracket member on each of said carriers extending to one side of said arms, work-supporting means, spacing members engagable therewith and rotatable in said brackets, and means for securing said spacing members in desired adjusted position.
30. 6. In an engine stand, a pair of spaced arms, a cross-piece, and rotatably mounted means carried by said arms for supporting said cross-piece, and means for securing said cross-piece to said supporting members at any chosen distance from said arms.
40. 7. In an engine stand, a pair of spaced arms, a cross-piece supported from said arms, said cross-piece consisting of a pair of parallel bars spaced apart to form a narrow slot therebetween, a supporting bolt in said slot, and means for adjustably securing said bolt to each of said parallel bars.
50. 8. In an engine stand, a pair of spaced arms, means adapted to be secured to one end of the engine to connect said arms, carriers on each of said arms, an inwardly extending bracket on each carrier, and means supported by said brackets for suspending the other end of said engine.
9. In a work-supporting stand, a pair of pivoted spaced arms, means adapted to be secured to one end of the work to connect said arms for simultaneous movement, carriers on each of said arms, an inwardly extending bracket on each carrier, and means supported by said bracket for suspending the other end of said work.
65. 10. In an engine stand, a truck, a standard mounted on said truck, a second standard mounted on said truck and movable with respect to said first-mentioned standard, means for moving said second standard, an arm pivotally supported by each of said standards, means for securing said pivoted arms at different distances from said truck, carriers slidably mounted on said arms, a slotted cross-piece supported from said carriers, and supporting means slidably mounted in said slot for securing an engine motor to said cross-piece.
70. 11. In an engine stand, a pair of spaced arms and a cross-piece supported from said arms, a grooved member slidably receiving one of said arms, a cone-shaped extension on said member, a support in which said extension is pivoted, and means for locking said arm, grooved member, and support against relative movement.
75. 12. In an engine stand, a base, a plurality of standards rising therefrom, a post in each standard telescoping therewith, means for locking said post and standard in desired adjusted position, an arm pivotally mounted in each post and secured thereto by a cone clutch, and a cross-bar supported from said arms.
80. 13. In an engine stand, a standard, a beam secured to said standard, a second standard adjustable on said beam, a rail carried by each standard and pivoted about a common axis, a cross-piece secured to one rail and adjustably secured to the other rail, means 100 adjustable on said cross-piece to secure one end of an engine, and an inwardly extending bracket adjustable on one rail for securing the other end of the engine.
90. 14. In an engine stand, a standard, a beam secured to said standard, a second standard adjustable on said beam, a rail carried by each standard and pivoted about a common axis, a cross-piece secured to one rail and adjustably secured to the other rail, means 110 adjustable on said cross-piece to secure one end of an engine, and means adjustably carried by said arms, on the side of the pivot distant from the cross-piece, for supporting the other end of said engine.

ROBERT E. MANLEY.
